UNITED STATES PATENT OFFICE

108,692

DESIGN FOR A SPOON OR OTHER ARTICLE OF FLATWARE

Marwood A. Downs, Muncie, Ind., assignor to Ontario Manufacturing Company, Muncie, Ind., a corporation

Application December 30, 1937, Serial No. 73,986

Term of patent 14 years

To all whom it may concern:

Be it known that I, Marwood A. Downs, a citizen of the United States, residing at Muncie, in the county of Delaware and State of Indiana, have invented a new, original, and ornamental Design for a Spoon or Other Article of Flatware, of which the following is a specification, reference being had to the accompanying drawing, forming part thereof.

In the drawing, Fig. 1 is a front plan view of a spoon or other article of flatware, showing my new design; Fig. 2 is a sectional view taken on line 2—2 of Fig. 1; and Fig. 3 is a section taken on the line 3—3 of Fig. 1.

The essential feature of the design resides in the ornamentation on the spoon handle as shown.

I claim:

The ornamental design for a spoon or other article of flatware, substantially as shown and described.
